UNITED STATES PATENT OFFICE.

EDWARD C. BEHRENS, OF READING, PENNSYLVANIA, ASSIGNOR TO ED. A. KELLY, OF SAME PLACE, AND CHRISTOPHER H. LOVELAND, OF SCRANTON, PENNSYLVANIA.

DESIGN FOR A TOY.

SPECIFICATION forming part of Design No. 29,746, dated November 29, 1898.

Application filed June 3, 1898. Serial No. 682,490. Term of patent 7 years.

To all whom it may concern:

Be it known that I, EDWARD C. BEHRENS, a citizen of the United States, residing at Reading, in the county of Berks and State of Pennsylvania, have invented and produced a new and original Design for a Toy; and I do hereby declare the following to be a full, clear, and exact description of the same, reference being had to the accompanying drawings, forming a part thereof.

This is a new and original design for toys.

In the accompanying drawings, Figure 1 is an elevation. Fig. 2 is a vertical longitudinal sectional view on line $x-x$, Fig. 1. Fig. 3 is a cross-sectional view on line $y-y$, Fig. 1.

Referring to the drawings, A designates a cylindrical plug. Projecting vertically from

this plug are a series of feathers α , the longitudinal edges of which abut, so that conjointly the several feathers form a triangle ²⁰ in horizontal cross-section.

The essential feature of my design is the upward projection in the form of a triangle in horizontal section.

I claim as my invention—

The design for a toy substantially as shown and herein described.

In testimony whereof I affix my signature in presence of two witnesses.

EDWARD C. BEHRENS.

Witnesses:

ED. A. KELLY,
C. H. LOVELAND.
